CLOTHESPIN

Otto James Flieler, Cloyne, Ontario, Canada, assignor of twenty-five per cent to H. C. Elkington, Plevna, Ontario, Canada

Application July 13, 1939, Serial No. 284,265
In Canada July 13, 1938

6 Claims. (Cl. 24—250)

This invention relates to improvements in a clothes pin and appertains particularly to one adapted to be secured in place by a locking clamp and thus prevent clothes being torn off the line by strong wind.

A further object of the invention is to provide a clothes pin formed of a pair of confronting bars, that serve as jaws, pivotally connected by a spring member that normally holds the jaws open and a clamping member operating against the action of the spring to lock the jaws closed.

A still further object of the invention is the provision of a clothes pin of the nature and for the purpose described that is characterized by structural simplicity, durability, efficiency and low cost of production, being thereby rendered commercially desirable.

To the accomplishment of these and related objects as shall become apparent as the description proceeds, the invention resides in the construction, combination and arrangement of parts as shall be hereinafter more fully described, illustrated in the accompanying drawing and pointed out in the claims hereunto appended.

The invention will be best understood and can be more clearly described when reference is had to the drawing forming a part of this disclosure, wherein like characters indicate like parts throughout the several views.

In the drawing:

Figure 1 is a side elevation of the clothes pin open;

Figure 2 is a similar view thereof of the pin closed, and

Figure 3 is a plan view of Figure 2.

The device is composed of a pair of confronting companion bars 5 that are substantially rectangular in cross section. These bars are thicker near the end 6 that serves as a jaw tapering therefrom on the inside to the far or tail end 7. The confronting jaws 6 are bevelled as at 8 toward the mouth where their confronting faces are cut out to provide the arcuate seats 9.

About midway of their length the bars 5 have a transverse groove 10 to receive an interposed transversely arranged coil spring 11 whose opposite ends 12 extend rearwardly and then bend inwards at right angles to respectively engage the outsides of the bars 5 where shallow grooves 13 are provided for their accommodation. The bars 5 thus teeter on the coil spring 11 whose overlying ends pinch the tails 7 together normally holding the jaws 6 open.

Between the transverse coil spring 11 and the jaws 6, both bars are perforated as at 14, to receive a split pin 15 anchored at the bottom by a keeper 16 and in whose looped upper end 17 a spring clamping cam member 18 is confined.

5 The handle end 19 of the clamp is formed as an S that continues at its cam clamping end into a spiral 20. The spiral cam is slotted centrally in from its end with a deep notch 21 and just beyond the inner end of this notch is further provided with a rectangular perforation 22, the portion between said notch and perforation being confined in the loop 17 of the split pin 15.

15 When the cam member 18, which may be of resilient material, is released the jaws of the clothes pin open under the action of the spring 11 so the device is readily available to apply to the clothes line to hold an article securely thereon. When applied to the line, the cam member 18 is operated by swinging the handle end 19 thereof through an angle of approximately 180° on its portion confined in the loop 17 of the split pin 15 thereby causing the spiral spring fingers of the slotted spiral 20 to bear down on the top 20 of the adjacent bar 5 to close the jaws 6 against the spring 11.

25 From the foregoing description taken in connection with the accompanying drawings, it will be manifest that a clothes pin is provided that will fulfil all the necessary requirements of such a device but as many changes could be made in the above description and many apparently widely different embodiments of the invention may be constructed within the scope of the appended claims without departing from the spirit or scope thereof, it is intended that all matters contained in the said accompanying specification and drawings shall be interpreted as illustrative and not in a limitative or restrictive sense.

30 Having thus described the invention, what is claimed as new is:

1. A clothes pin comprising a pair of separate, confronting bars, jaws formed on one end thereof, a transversely disposed coil spring therebetween, on which said bars teeter, normally holding said jaws open, and a cam locking member held to one bar between the spring and its jaw end and bearing against the outer side of the other of said bars for closing said jaws against the action of said spring.

2. A clothes pin comprising a pair of separate, confronting bars, jaws formed on one end thereof, a spring between said members normally holding said jaws open, a split pin passing through said bars between said spring and their

normally open end, and a cam member held by said pin and working against the adjacent bar to clamp said jaws closed.

3. A clothes pin comprising a pair of separate, confronting bars, jaws formed on one end thereof, a spring between said members normally holding said jaws open, a split pin passing through said bars near their normally open end, and a spiral spring cam member held by said pin and working against the adjacent bar to clamp said jaws closed.

4. A clothes pin comprising a pair of confronting companion bars substantially rectangular in cross section, a coil spring disposed transversely between said bars approximately mid-way of their length having its ends extended and bent at right angles to engage the outsides of said respective bars tending to hold the engaged ends of said bars that teeter on said transverse spring closed and the opposite ends of said bars, that serve as jaws, open; a perforation through both of said bars between said transverse spring and the normally open ends, a pin through said perforation, a keeper on one end of said pin and a loop on the other, and a spring locking cam held in said loop and adapted to operate against the outer face of the adjacent bar.

5. A clothes pin comprising a pair of separate, confronting bars substantially rectangular in cross section, jaws formed on one end of said bars, said bars being tapered on their inner sides at the opposite end to provide bevelled tails, a

transversely disposed coil spring between said bars approximately midway of their length on which said bars teeter, arms from said spring engaging the outer sides of the bevelled tails of said respective bars normally holding the jaws open and a cam locking member anchored to one jaw and operating against the outer side of the opposite one for closing said jaws against the action of said spring.

6. A clothes pin comprising a pair of separate confronting bars substantially rectangular in cross section, one end of said bars being formed as jaws and the other end of said bars being tapered on their inner sides to provide oppositely bevelled tails, a transversely disposed coil spring between said bars approximately midway of their length on which said bars teeter and an arm from each of the opposite ends of said spring being bent to extend over the outer side of the 15 tapered tails of said respective bars whereby said tapered tails are pinched together so that said bars teetering on said transverse coil spring cause the opposite jaw ends to open, said coil spring and its extended overlying arms serving also to hold said pair of bars against accidental relative displacement, a split pin passing freely through said bars between said spring and their normally open jaw ends and a cam member held by said pin and working against the adjacent bar to clamp said jaws closed against the action of said spring.

OTTO JAMES FLEILER.
